US0D1047582S

(12) **United States Design Patent** (10) **Patent No.:** **US D1,047,582 S**
(45) **Date of Patent:** **** Oct. 22, 2024**

(54) **COOKWARE HANDLE MOUNT**

(71) Applicant: **Sea to Summit Pty Ltd**, Rivervale (AU)
(72) Inventors: **Thomas M. Schilperoort**, Perth (AU); **Daniel C. Booker**, Melbourne (AU); **David R. Chapman**, Melbourne (AU)
(73) Assignee: **Sea to Summit Pty Ltd**, Rivervale (AU)
(**) Term: **15 Years**
(21) Appl. No.: **29/874,128**

(22) Filed: **Apr. 14, 2023**

(51) LOC (14) Cl. **07-02**
(52) U.S. Cl. **USPC D7/393**

(58) **Field of Classification Search**

(57) **CLAIM**

The ornamental design for a cookware handle mount, as shown and described.

DESCRIPTION

FIG. 1 is a top isometric view of a cookware handle mount showing the design.

FIG. 2 is a bottom isometric view thereof;

FIG. 3 is a front elevation view thereof;

FIG. 4 is a rear elevation view thereof;

FIG. 5 is a right side elevation view thereof;

FIG. 6 is a left side elevation view thereof;

FIG. 7 is a top plan view thereof; and

FIG. 8 is a bottom plan view thereof; and,

FIG. 9 is an isometric environment view showing the cookware handle mount in an environment of use on a cookware vessel.

The dashed lines showing a cookware vessel in FIG. 9 illustrate environment and form no part of the claimed design. The dashed lines shown in FIGS. 1-8 illustrate portions of the cookware handle mount that form no part of the claimed design.

1 Claim, 6 Drawing Sheets
